AIR DRIVEN TUNING FORK

Filed June 4, 1929

UNITED STATES PATENT OFFICE

RICHARD HOWLAND RANGER, OF NEWARK, NEW JERSEY, ASSIGNOR TO RADIO CORPORATION OF AMERICA, A CORPORATION OF DELAWARE

AIR-DRIVEN TUNING FORK

Application filed June 4, 1929. Serial No. 368,404.

The present invention relates broadly to a method and means for driving tuning forks and the like, and forms a divisional part of my copending application, Serial No. 5 169,620, filed Feb. 19, 1927.

More specifically, my invention is directed to and relates to a method and means by which quartz or steel tuning forks, and the like, may be driven or vibrated by means of 10 an air jet so as to eliminate all electrical contacts from the drive therefor.

Heretofore, it has been most difficult to drive tuning forks and especially quartz tuning forks since it was necessary to add 15 pieces of steel to a quartz tuning fork in order that the fork might be electrically driven, and this addition of steel or other metallic substance to the end of the fork 20 tine, it was observed, had a more or less detrimental effect upon the accuracy of the fork itself.

As a principal object of my invention, I, therefore, sought to produce a novel means 25 for controlling tuning forks by means of an air jet.

Still other objects of my invention are to provide in a manner to be hereinafter set forth an air means for driving tuning forks and the like which is relatively simple in 30 its construction and arrangement of parts, as well as a system which is durable, compact, efficient in its use, conveniently operated, readily set up, fool-proof, and relatively inexpensive to install.

The novel features which I believe to be characteristic of my invention are set forth in the hereinafter appended claims, but the invention itself, both as to its organization and method of operation together with further objects and advantages thereof, will be 40 best understood by making reference to the following specification when read in connection with the accompanying drawing, wherein, the single figure thereof is a schematic illustration, partly in section, of an air vibrating means for driving a tuning fork in accordance with my invention.

Now, to make reference to the above identified drawing which forms a part of my disclosure, air from any desired source of con-

stant pressure (not shown) may be carried through an air hose 1 to an air chamber 3 through any desired type of air inlet, for example, by a tube 5 adapted to permit the inward passage of air. Branching off from either side of the air chamber 3 at points 90° 55 from the inlet of the tube 5 are two openings 7 and 9 which open the tines of a tuning fork, generally designated 11. Placed against each of the openings 7 and 9 and flush with them are a pair of cylindrical plug members 13 and 15 respectively, which have their opposite ends 17 and 19 flattened and attached to the ends of the tines 21 and 23 respectively of the tuning fork by means of a 60 screw or some other equivalent means, or which may be, if desired, cast directly as a part of the fork itself. Leading out from the other end of the air chamber, that is, the end directly opposite the point of air entrance of the tubular member 5, is a fourth 65 opening or duct 25 leading to a tubular member 27, which I shall hereinafter describe as an "air resonant column."

The tuning fork 11 may be mounted from 70 its end 29 by any desired and suitable form of clamping means (not shown), and the tines 21 and 23 thereof extend outwardly from the clamping or support means toward the air chamber 3 to the point where the tines are 75 fastened to the plugs 13 and 15 which, as above described, rest against the air chamber and through the openings of which air which is supplied to the air chamber under pressure from the source passes out to drive the fork in a manner to be hereinafter described.

It has been found that the tuning fork, through the attached plugs 13 and 15, acts as a baffle on the outlet portions 7 and 9 of the air chamber 3, and as air fills the air chamber, 80 it gradually forces the plugs 13 and 15 outwardly. Upon the outward movement of the fork tines, the plugs 13 and 15 are moved a slight amount away from the air chamber 85 and the air pressure therein is thus released. After the tine of the fork has been moved or forced outwardly, it inherently tends to return to its original position through its own elasticity and in so doing brings the plug members 13 and 15 back to their former po- 90

sition against the outlet from the air chamber so as to again charge the chamber with air.

As will readily be seen, the charging and discharging of the chamber 3 with air supplied through the air inlet tube 1 is a function of the natural period of vibration of the tuning fork member 11, and in order to support this vibration, the resonant air column 27 may be adjusted by loosening the support 28 therefor and then moving the slide member 31 contained within the resonant air chamber 27, and supported by a supporting bracket 32, for example, either in or out with respect to the air chamber 3 by grasping the knob 33 so as to push the tube 31 into the air chamber or to retract the tube from the resonant air chamber. By such adjustment, the natural period at which the air may fill the chamber 3 may be made to substantially correspond to the fork frequency.

It may, therefore, be seen that there is an alternate charging and discharging action of the air taking place in the air chamber which takes place in accordance with the period of vibration of the fork. This charging and discharging action gives a good clean cut vibration to the fork, and, by use of the method herein described, it is possible to have an exceedingly low intensity of vibration of the fork, and, naturally, the lower the vibration intensity, the more constant the period of the fork. By means of the air, it is possible to work with a much less intensity of vibration than is normally possible with an electrically driven fork, and it may also be seen, where the rate at which the air is permitted to fill the air chamber is made the same as the period of the fork, that this in itself means accuracy in vibrational periods of the fork. Under the above described conditions, the air which is led to the air chamber is under constant pressure, and when the air chamber itself is made broadly resonant to the period of the tuning fork by suitable adjustment of the tubular member 33 within the tube 27 forming the resonant air column, there is little or no difficulty in sustaining vibrations of the fork with very low air pressure, which may, for example, be of the order of two pounds per square inch, although it is to be understood that I do not limit myself to such a value but other air pressures may be substituted where found desirable.

Vibrational impulses from the fork may be utilized in any desirable manner for synchronizing movable apparatus or for utilizing the air leaving the resonant air column for the purpose of applying corrective impulses upon brakes for motors and the like, as disclosed in my above named copending application of which this forms a divisional part.

65 Other modifications and changes to the ar-

rangement herein disclosed will at once suggest themselves to those skilled in the art to which the invention relates, and I, therefore, believe myself to be entitled to make any and all modifications thereof that fall fairly within the spirit and scope of the hereinafter appended claims.

Having now described my invention, what I claim and desire to secure by Letters Patent is the following:

70 1. A means for vibrating a tuning fork which comprises a tuning fork, a chamber provided with openings adjacent to the tines of said fork, a plug member extending toward and adjacent said opening associated with each of said tines, and means for forcing air into said chamber, whereby an air pressure adapted to force said tines outwardly by means of said plugs is produced within said chamber.

75 2. A means for vibrating a tuning fork or the like which comprises a tuning fork, a resonant air chamber provided with openings adjacent the tines of said fork, a plug member extending toward and adjacent said openings associated with each of said tines, and means for forcing air into said chamber whereby pressure adapted to force said tines outwardly by means of said plugs is produced within the said chamber.

80 3. A system for producing vibration of tuning forks and the like which includes a resonant air chamber, means for supplying air at a predetermined pressure to said air chamber, and means associated with said air chamber for utilizing the air pressure contained therein for vibrating the said tuning fork.

85 4. A system for vibrating tuning forks and the like which includes a resonant air chamber having an opening at one end thereof, means for supplying air at a predetermined pressure to said opening, said chamber also having openings extending in two directions therefrom at substantially right angles to the said air inlet opening, a plug member carried by each of said tines of said tuning fork and extending within said last named openings, means provided by said air pressure within said chamber for forcing said plugs outwardly therefrom and thereby vibrating said fork, and means opposite said air inlet opening for adjusting the resonant period of said air chamber to substantially correspond to the natural period of vibration of said tuning fork.

90 RICHARD HOWLAND RANGER.
